UNITED STATES PATENT OFFICE.

ADOLPH BERKOVITZ AND SAMUEL FRIED, OF NEW YORK, N. Y.

DESIGN FOR A PHONOGRAPH-CABINET.

51,630.

Specification for Design.

Patented Jan. 1, 1918.

Application filed October 18, 1917. Serial No. 197,322. Term of patent 14 years.

To all whom it may concern:

Be it known that we, ADOLPH BERKOVITZ and SAMUEL FRIED, a citizen of the United States, and a subject of the King of Hungary, respectively, residing at New York, in the counties of New York and Bronx, respectively, and State of New York, have invented a new, original, and ornamental Design for Phonograph-Cabinets, of which the following is a specification, reference being

had to the accompanying drawing, forming part thereof.

Figure 1 is a front elevation of a phonograph cabinet, showing our new design; and Fig. 2 is a top plan view thereof.

We claim:

The ornamental design for a phonograph cabinet, as shown.

ADOLPH BERKOVITZ.
SAMUEL FRIED.
